Primary Examiner — Kevin K Rudzinski*Assistant Examiner* — Richard E Yenchesky(74) *Attorney, Agent, or Firm* — Kinney & Lange, P.A.(57) **CLAIM**

The ornamental design for a frame for high-pressure cleaner as shown and described.

DESCRIPTION

FIG. 1 is a front perspective view;

FIG. 2 is a rear view;

FIG. 3 is a right side view;

FIG. 4 is a left side view;

FIG. 5 is a top plan view;

FIG. 6 is a bottom plan view; and,

FIG. 7 is a perspective view.

The broken lines shown in the Figures represent portions of the frame for high-pressure cleaner that form no part of the claimed design.
